UNITED STATES PATENT OFFICE

2,127,559

SINK

Vincent J. Graf, Detroit, Mich., assignor to Briggs Manufacturing Company, Detroit, Mich., a corporation of Michigan

Application July 27, 1936, Serial No. 92,803

9 Claims. (Cl. 4—187)

This invention relates to sinks, wash basins or the like, and to the fabrication thereof by stamping operations from sheet metal, preferably sheet steel, and more particularly to the formation of articles of the above character from a single metal sheet or blank and preferably in such manner as to permit uniformly satisfactory enamel coating thereof.

One of the objects of the present invention 10 is to provide a pressed metal sink having substantially two basins, a relatively shallow main basin and a relatively deep sub-basin, said sub-basin being located in the bottom of said main basin, with the bottom of the main basin surrounding the sub-basin at all four sides thereof.

Another object of the invention is to provide a pressed metal sink having a main basin and a sub-basin provided at the bottom of said main basin, and having suitable drain beads provided 20 at one or at both sides of said sub-basin, thus causing the portion of the bottom of the main basin to serve as a single or a double drain-board.

A still further object of the invention is to 25 provide a novel pressed metal sink having the upright back wall of the basin or fluid receiving bowl extended rearwardly to provide a relatively wide horizontal shelf or ledge and thence upwardly to provide a splash-back.

A still further object of the invention is to 30 provide an integrally formed pressed metal sink of the foregoing character in which the sub-basin is provided with a drain hole located off-center with respect to said sub-basin and in 35 relatively close proximity to the upright back wall of the basin, thus decreasing the length and overhang of the water spout.

It is a still further object of the invention 40 to provide a method of forming the sink of the above character from a single sheet metal blank, which method includes the steps of forming a sub-basin, and thereupon simultaneously forming the main basin and the beads at the bottom thereof, and in which the back ledge or shelf and the rim extending around three sides of the bowl all lie in the same horizontal plane and are formed seamlessly with the upright splash-back.

Other objects of this invention will appear in 45 the following description and appended claims, reference being had to the accompanying drawings forming a part of this specification wherein like reference characters designate corresponding parts in the several views.

Fig. 1 is a perspective view of a double drain-board sink embodying the present invention.

Fig. 2 is a transverse vertical sectional view of the structure shown in Fig. 1, looking in the direction of the arrows, section being taken along 5 the line 2—2 of Fig. 1.

Fig. 3 is a perspective view of a left hand drain-board sink having drain beads provided in a single group at the bottom of the main basin and on the left hand side of the sub-basin. 10

Fig. 4 is a longitudinal sectional view of the structure shown in Fig. 3, looking in the direction of the arrows, section being taken on the line 4—4 of Fig. 3.

Fig. 5 is a perspective view of a right hand 15 drain-board sink similar to that illustrated in Fig. 3, but having the drain beads located at the right hand side of the sub-basin.

Fig. 6 is a transverse sectional view of the structure shown in Fig. 5, looking in the direction of the arrows, section being taken on the line 6—6 of Fig. 5.

Fig. 7 is a perspective view showing a metal 20 blank from which the sink of Fig. 1 is fabricated, with a sub-basin preliminarily formed.

Fig. 8 is a perspective view illustrating a succeeding step in fabricating the sink, at which the shallow main basin and two groups of beads at the bottom thereof are formed in one operation.

Fig. 9 is a transverse sectional view on the 30 line 9—9 of Fig. 8.

Fig. 10 is a perspective view illustrating the 35 step of simultaneously forming the main basin and the drain beads in a blank for the right hand sub-basin sink.

Fig. 11 is a perspective view illustrating the operation of trimming the metal blank for the sink of Fig. 1.

Fig. 12 is a perspective view illustrating the 40 step of simultaneously forming the shelf and the splash-back or panel.

Fig. 13 shows in perspective the metal blank 45 after drawing the flanges of the splash-back and embossing the face thereof.

Fig. 14 is a perspective view illustrating the 50 operation in which the excess metal at the corners of the splash-back is removed.

Fig. 15 shows in perspective the metal blank 55 after drawing the depending apron flange around three sides thereof, the dotted line indicating the position of the edge before the drawing operation.

Fig. 16 is a sectional view on the line 16—16 of Fig. 15.

Fig. 17 is a perspective view with sections 55

broken away illustrating the operation of forming the wall flanges along the top and ends of the splash-back, the dotted line indicating the position of the metal before said operation.

5 Fig. 18 is a view similar in part to Fig. 17 illustrating the operation of forming the bottom flange along the lower edge of the depending apron.

10 Fig. 19 shows in perspective the sink blank after the operation of piercing the faucet and spout holes.

15 Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

20 In the drawings I have shown, by way of example, three structures embodying my invention. Referring particularly to Fig. 1, the same represents a sink or wash basin comprising generally a horizontally extending face 20 in which there is formed a main or shallow basin 30, said basin being surrounded at its four sides by said horizontal portion 20. The latter comprises in the finished sink a back ledge or shelf 21 and a continuous rim 22, 23, 24 merging smoothly into the shelf and all forming a co-planar horizontal 25 surface surrounding the main and sub-basins. In the bottom of said main basin 30 there is formed a second basin or fluid receiving bowl 31, which I term the sub-basin. It is an important feature of my invention, that the bottom of the main basin 30 extends around all four sides of said sub-basin 31, the corresponding parts of said bottom being indicated by the characters 32a, 32b, 32c and 32d. The back edge of the horizontal portion 20 merges seamlessly into an upright or vertically 30 extending splash-back indicated generally by the numeral 40. The face 41 of said splash-back 40 may be suitably embossed, such for example as indicated by the panel embossing 42. A desired number of suitable faucet and spout holes 43, 43, 35 is provided in the splash-back. At its top and ends the splash-board 40 is provided with rearwardly extending flanges such as 44, 45, and 46, which flanges are in turn provided with narrow wall flanges 47, 48 and 49, respectively (see Fig. 35 17). The ledge 21 which extends between the main basin 30 and the splash-back 40 is made of such width as to permit its use as a shelf for such articles as glasses and the like. The continuous rim portions 22, 23 and 24 which extend around 40 the front and sides of the main basin 30 are preferably made somewhat narrower than the shelf 21. The horizontal rim portions 22, 23, 24 are turned downwardly to provide a continuous seam- 45 less depending apron, the respective portions 60 whereof being designated by the numerals 25, 26 and 27. The lower edges of said apron are provided with a substantially horizontal, continuous inwardly extending flange such as indicated at 28.

46 The bottom 32 of the main basin 30 is preferably made slightly sloping toward the sub-basin 31, and it is provided with a number of suitably disposed drain grooves or beads such as 33, 33. In the structure shown in Fig. 1 the sub-basin 31 is located substantially in the middle of the bottom 32, and said beads 33, 33 are arranged in

5 two groups at both sides of said sub-basin 31, thus providing a double drainboard sink, with portions 32a and 32b of the bottom 32 serving as drainboards.

10 The bottom 32 merges seamlessly into the walls 5 of the sub-basin 31, which sub-basin is made deeper than the main basin 30. The bottom 34 of the sub-basin 31 is made slightly sloping toward a drain hole 35, which hole is preferably located not at the center of said bottom 34, but 10 closer to the back wall 36 of the basin. By virtue of this construction it is possible to locate the spout outlet directly above the drain hole 35 without requiring the use of a spout of excessive length or overhang from the splash-back to the 15 fluid receiving bowl.

20 Referring to Fig. 3 there is shown in this instance a sink similar in part to the structure of Fig. 1, the sub-basin however being arranged to provide a so-called left hand drainboard sink. As 25 shown in Fig. 3, the sub-basin 31 is arranged at the right hand side of the bottom 32 of the main basin 30, there being a narrow ledge 52b between the sub-basin 31 and the right hand side wall of the main basin 30, and ledges 52c and 52d 25 formed by the bottom 30. In other words, while in the previous structure the portions 32a and 32b extending at both sides of the sub-basin 31 are substantially symmetrical in the structure of Fig. 3 the drainboard portion 32c is similar to the 30 drainboard portion 32a of the embodiment of Fig. 1 and is provided with beads such as 53, 53. The narrow ledge 52b has a width preferably equal to that of the ledge 52c and ledge 52d.

30 Referring to the embodiment illustrated in Fig. 35 5, the structure herein shown is a left hand sub-basin sink differing from the structure of Fig. 3 by the arrangement of the sub-basin 31 in the bottom 32 of the main basin 30. As can be clearly seen in Fig. 5, the sub-basin 31 is arranged 40 at the left hand side of said bottom 32, the narrow ledge 52a corresponding to the ledge 52b of the structure shown in Fig. 3 while the sloping portion 52b is provided with beads such as 63, 63 similar to the portion 32b of the structure of Fig. 1. Horizontal ledges 62c and 62d formed as a 45 part of the bottom 32 of the main basin 30 are located along the front and the back walls of said sub-basin 31. As in the previous embodiments the main basin extends at all four sides of the 50 sub-basin.

55 It will be clear in view of the foregoing, that my novel sink possesses many advantageous features not found in previous structures. Provision of the wide back ledge or shelf which is a 55 continuation of the top horizontal surfaces of the surrounding rim provides a conveniently located flat horizontal surface upon which articles, such as glasses and the like, may be safely and conveniently placed without interfering with the use of 60 the basin and drainboards.

65 Figs. 7 to 10, inclusive, illustrate preferred steps in the method of forming the sinks in accordance with the invention from a single sheet metal blank. In fabricating the double drainboard sink 65 of Fig. 1 a single sheet metal blank 70 is placed in a suitable press and the central portion is preliminarily drawn to provide the sub-basin 31, as illustrated in Fig. 7, this being accomplished by a suitably shaped dies. In a succeeding operation the blank is operated upon in suitable dies to form simultaneously the main basin 30 and the drain beads 33 in the bottom 32 thereof, as illustrated in Fig. 8. In the same or succeeding operations the sub-basin 31 may be re-struck 70 75

and completed as to shape and depth, as well as embossed for the drain hole 35 as indicated at 35a, and its bottom made sloping toward said embossed portion, as illustrated in Fig. 9. In 5 Fig. 10 there is shown a blank for the right sub-basin sink after similar operations have been performed thereon.

In accordance with the next preferred step in the method, the blank is preferably rough 10 trimmed around its edges 71, and a suitable shape facilitating further forming operations is given to the corners 72, 72 thereof.

In the following operation the metal in rear 15 of the upright back wall of the sub-basin 31 is formed or bent up along the line 74, 74 (see Fig. 11), thus simultaneously forming the shelf 21 and the face 41 of the back panel or splash-board 40 (see Fig. 12).

For forming the top and end flanges 44, 45 and 20 46 of the splash-back 40, the marginal metal of the upstanding portion formed in the preceding operation is pressed rearwardly, substantially along the dotted line 75 (Fig. 12), this being accomplished between suitable dies, the face 41 being preferably simultaneously embossed as at 25 42. The result of this operation is illustrated in Fig. 13, wherein the splash-back is shown provided with a continuous uninterrupted flange along its top and ends, the flanges at its ends merging seamlessly into the rear ends of the horizontal rim portions 22 and 24.

The blank having been drawn to the approximate form illustrated in Fig. 13, the next step in the method preferably consists in forming the 30 depending apron flange. This is effected by pressing or turning downwardly the marginal metal of the horizontally extending rim forming portion of the blank approximately along the dotted line 76 (see Fig. 14). As can be seen in Fig. 15 35 wherein the result of this operation is illustrated, there is thus produced a continuous depending apron consisting of seamlessly merging portions 25, 26 and 27, the rearmost extremities of the portions 25 and 27 merging seamlessly into the lowermost extremities of the splash-board flange portions 45 and 46, respectively, such, for instance, as indicated at 29.

In addition to the foregoing steps in the formation of the sink, succeeding forming operations are desirable to provide flanging along the lower 40 edge of the depending apron, such as shown at 28 (see Fig. 18), and providing a continuous wall flange along the rear flanged edges of the splash-board 40, comprised of mutually merging flange portions 47, 48 and 49 (see Fig. 17).

Fig. 19 shows the blank after the following operations of piercing and offsetting the drain hole 35, and piercing and countersinking the faucet and spout holes 43, 43.

In the present embodiment herein illustrated, I have set forth a sequence of steps by which the method may be satisfactorily performed. The invention, however, is not limited to the sequence herein given, as obviously certain steps may be combined or rearranged in different order. If desired, the splash-board panel and the horizontal rim and ledge may be formed first, after which the two basins may be pressed out. In certain instances the drainboard may be omitted, and the steps in the method of forming such modified structure be correspondingly rearranged.

From the foregoing it will be seen that the sub-basin or fluid bowl of the sink is separated from the substantially flat top horizontal rim 75 (which extends around three sides thereof) by a

continuous narrow ledge and upright shoulder forming part of the primary basin and is also separated from the flat top back ledge or shelf by a corresponding narrow ledge and shoulder. This construction prevents, to a considerable extent, splashing of water from the fluid bowl over the flat rim. The back shelf and rim merge smoothly into one another and seamlessly into the splash-back thus providing a smooth seamless surface, free of welds, which may be enamel coated satisfactorily in production so as to be free from unsightly blemishes.

I claim:

1. A pressed metal sink comprising a flat metal sheet having a relatively shallow primary basin 15 pressed therein and a relatively deep sub-basin pressed in the bottom of the primary basin, the bottom of said primary basin forming a ledge surrounding all four sides of the sub-basin, the marginal edges of the primary basin comprising 20 a substantially horizontal rim formed seamlessly as a part of a depending apron extending continuously around three sides of the basin and a substantially horizontal back ledge extending rearwardly from the back walls of the basins and terminating seamlessly in an upright splash back, said ledge forming a shelf extending the full 25 length of the sink.

2. A sink pressed from a single sheet of metal to provide a substantially rectangular fluid receiving bowl terminating in a sloping drainboard at at least one side thereof and in an upright splash back, there being a turned or rolled rim surrounding three sides of the bowl and formed as a part of a depending apron also extending 30 around three sides of the bowl; the splash back being bent upwards to provide a substantially flat top horizontal shelf between the splash back and bowl, said shelf being of uniform depth throughout the major portion of the length of 35 the bowl and merging seamlessly into the ends of the rim and the splash back throughout the length of the latter, said splash back having a continuous rearward flange along the top and ends thereof terminating in wall flanges, and said apron having inturned flanges along its 40 lower edge, the junctures of said apron and splash back flanges being seamless.

3. A sink pressed from sheet metal to provide a fluid receiving bowl terminating in a sloping drainboard at at least one side thereof and in an upright splash back, there being a turned rim surrounding three sides of the bowl formed as a part of a depending apron also extending around three sides of the bowl; the splash back being bent upwards on a line offset rearwardly 50 from the rear wall of the bowl to provide between said wall and splash back a substantially flat horizontal ledge, said drainboard extending in a plane below the plane of the rim and said ledge and rim lying in the same plane.

4. A sink pressed from sheet metal to provide a fluid receiving bowl terminating in a sloping drainboard at at least one side thereof and in an upright splash back, there being a turned rim surrounding three sides of the bowl formed as a part of a depending apron also extending around three sides of the bowl; the splash back being bent upwards on a line offset rearwardly from the rear wall of the bowl to provide between said wall and splash back a substantially flat horizontal ledge extending uninterruptedly the full length of the sink, said drainboard extending in a plane below the plane of the rim and said ledge and rim lying in the same plane.

5. A sink pressed from sheet metal to provide a fluid receiving bowl terminating in a sloping drainboard at at least one side thereof and in an upright splash back, there being a turned rim surrounding three sides of the bowl formed as a part of a depending apron also extending around three sides of the bowl; the splash back being bent upwards on a line offset rearwardly from the rear wall of the bowl to provide between said wall and splash back a substantially flat horizontal ledge, said drainboard extending in a plane below the plane of the rim and said ledge and rim lying in the same plane, the rear wall of the bowl having along its upper edge a longitudinal offset forming a continuation of the rear longitudinal edge of the drainboard.
6. A pressed metal sink comprising a generally rectangular fluid receiving bowl terminating in a sloping drainboard at at least one side thereof and in an upright splash back, there being a turned rim surrounding three sides of the bowl formed as a part of a depending apron also extending continuously around three sides of the bowl; a longitudinal substantially flat horizontal shelf interposed between the bowl and splash back and extending the full length of the sink in the plane of the rim.
7. A pressed metal sink comprising a generally rectangular fluid receiving bowl terminating in a sloping drainboard at at least one side thereof and in an upright splash back, there being a turned rim surrounding three sides of the bowl

formed as a part of a depending apron also extending continuously around three sides of the bowl; a longitudinal substantially flat horizontal shelf interposed between the bowl and splash back and extending the full length of the sink in a plane offset upwards from the plane of the drainboard.

8. A pressed metal sink comprising a flat metal sheet having a relatively shallow primary basin pressed therein and a relatively deep sub-basin pressed in the bottom of the primary basin, the bottom of said primary basin forming a ledge surrounding all four sides of the sub-basin and the rim of the primary basin comprising a substantially flat top horizontal ledge extending in the same plane around four sides thereof and providing at the back a shelf for articles.

9. A sink pressed from a single sheet of metal to provide a fluid receiving basin and an upright splash panel, the margin of the basin comprising a continuous substantially flat top ledge entirely surrounding the same and lying in one plane, the ledge at the back of the basin being sufficiently wide to provide a shelf for articles and merging seamlessly into the splash panel, and the ledge at the remaining three sides of the basin being relatively narrower and formed as a part of a depending apron, the lower edge of the apron being flanged inwardly and the splash panel having a continuous rearward flange along its top and ends terminating in wall flanges.

VINCENT J. GRAF.
